[57] CLAIM

The ornamental design for a tooth brush with removable head, as shown and described.

DESCRIPTION

FIG. 1 is an exploded perspective view of a tooth brush with removable head showing my new design;

FIG. 2 is a side elevational view thereof;

FIG. 3 is a front view thereof;

FIG. 4 is an assembled rear view thereof;

FIG. 5 is a top plan view thereof; and,

FIG. 6 is a bottom plan view thereof.

The side opposite to that shown in FIG. 2 is a mirror image thereof.
